(57) **CLAIM**

The ornamental design for a disc amusement device as shown and described.

DESCRIPTION

FIG. 1 is a top perspective view showing the new, original, and ornamental design of a disc amusement device;

FIG. 2 is a right side elevation view thereof, the left side, front side, and rear side elevation views being a mirror image and therefore not shown; and,

FIG. 3. is a top plan view thereof, the bottom plan view being a mirror image and therefore not shown.

The circular broken lines shown on the outer perimeter of the device in FIGS. 1-3 are air passage holes and form no part of the claimed design.
